UNITED STATES PATENT OFFICE

151,464

DESIGN FOR AN AIR FILTER

Niels H. F. Olsen, Dearborn, Mich.

Application June 20, 1947, Serial No. 139,845

Term of patent 14 years

(Cl. D62—4)

To all whom it may concern:

Be it known that I, Niels H. F. Olsen, a citizen of the United States, residing at Dearborn, Wayne County, Michigan, have invented a new, original, and ornamental Design for an Air Filter, of which the following is a specification, reference being had to the accompanying drawings, forming a part thereof, wherein:

Fig. 1 is a top plan view of an air filter embodying my new design:

Fig. 2 is a side elevation, and

Fig. 3 is an end elevation thereof.

I claim:

The ornamental design for an air filter, as shown.

NIELS H. F. OLSEN.
